WHEEL TRUING MECHANISM

Ralph E. Flanders and Lee M. Davis, Springfield, Vt., assignors to Jones & Lamson Machine Company, Springfield, Vt., a corporation of Vermont

Application August 26, 1937, Serial No. 160,956

10 Claims. (Cl. 125—11)

This invention relates to mechanism for truing grinding wheels and has for an object to provide for ready adjustment of the motion of the truing devices so that the faces of the grinding wheel may be trued exactly to various angles.

5 A further object is to provide an improved mechanism for effecting traverse of the truing tools along faces of the wheel.

10 A still further object is to provide a truing mechanism having the desired characteristics hereinbefore mentioned and which is particularly suitable for truing the faces of wheels for grinding threads.

15 A further object is to provide means for facilitating the control of the speed of rotation of the grinding wheel in order to maintain the desired surface cutting speed of the wheel as its diameter is reduced by wear and truing.

20 For a more complete understanding of this invention, reference may be had to the accompanying drawings showing one embodiment thereof by way of example, in which

25 Figure 1 is a fragmentary rear end elevation of a thread-grinding machine showing a wheel-truing mechanism embodying the invention.

Figure 2 is a fragmentary side elevation showing a portion of the mounting of the truing mechanism.

30 Figure 3 is a transverse section through the truing mechanism on the line 3—3 of Figure 4.

Figure 4 is a detail longitudinal section on the line 4—4 of Figure 1.

35 Figure 5 is a horizontal section through the truing mechanism on the line 5—5 of Figure 6.

Figure 6 is a section on line 6—6 of Figure 5.

Figure 7 is a detail section on line 7—7 of Figure 6.

Figure 8 is a detail section on line 8—8 of Figure 4.

40 Figure 9 is a front end elevation of the truing mechanism.

Figure 10 is a detail section on line 10—10 of Figure 6.

Figure 11 is an exploded perspective view of a 45 truing device adjusting mechanism.

Figure 12 is a fragmentary front elevation of the machine showing arrangements for facilitating adjustment of the grinding wheel speed in accordance with its decreasing diameter due to wear and truing.

50 Figures 13 and 14 are elevations to a larger scale of certain indicating plates shown in Figure 12.

Figure 15 is a wiring diagram of the wheel driving motor control.

The truing mechanism herein shown is illustrated as used in connection with a thread grinding machine of the general type shown in the Flanders Patent No. 1,739,753, granted December 17, 1929. The grinding wheel is shown at 1 5 carried by a shaft 2 and journaled in a slidable frame portion 3, this portion 3 being so mounted as to be moved toward and from the work as illustrated in the Flanders patent. Upon the frame 3 which carries the grinding wheel is arranged a wheel-truing mechanism which, as herein illustrated, comprises an angularly adjustable cylindrical casing 5 and an angularly fixed portion 6. This fixed portion 6 is guided for axial motion from and toward the wheel 1 as on a 10 guide bar 7, the part 6 being provided with a slotted lower end at 8 which slidably engages the bar 7. This guide bar 7 is secured as by one or more screws 9 to a frame portion 10 movable toward and from the work with the frame portion 3. The casing 5 may be secured in its angularly adjusted relation to the part 6 as by means of the bolt and slot connections at 15 shown best in Figure 1 and a series of bolts 15a passing through the portion 6, outside of the casing 5 and threaded into a clamping segment 11 20 engaging an extension on a cover plate 12 secured to the end of the casing 5 as by screws 13. The two parts 5 and 6 together comprise a carriage for supporting the wheel-truing mechanism 25 as will later be more specifically described, and this mechanism as a whole being supported on rollers 16, is moved from and toward the axis of the grinding wheel in order to effect traverse of the truing devices along the side faces 30 of the wheel. It is also adjusted toward the wheel as the wheel is trued, and this mechanism, with the adjusting for wheel truing, may be driven from the main drive mechanism of the machine, as shown in the Flanders patent hereinbefore 35 mentioned. Portions of connections for effecting this drive are shown in Figure 4, these comprising a shaft 20 journaled in bearings 21 and 22 of the main frame of the machine, the shaft 20 being provided with a driving gear 23 which may 40 be driven from the main drive mechanism in any suitable manner and at suitable times, as at a limit of traverse between the grinding wheel and the work being ground. This shaft 20 has secured thereto a pinion 24 which meshes with 45 a long gear 25 journaled on a shaft 26 secured in the frame portion 10 of the wheel slide. The long gear provides for driving connections from the shaft 20 throughout the range of motion of the wheel in feeding toward and retracting from 50 55

the work to be ground. This long gear 25 meshes with a gear 27 secured to a shaft 28. This shaft 28 is journaled at one end in a bearing 29 and toward its other end is threaded at 30 and has threaded engagement with a nut 300 secured in a wall member 31 shown as integral with the frame portion 10. Thus as the long gear 25 is rotated, the gear 27 is also rotated and the shaft 28 is not only rotated but is given a lengthwise motion due to its threaded engagement with the nut 300. This threaded portion 300 extends through a double arcuate slot 32 in an annular guide member 33 forming part of the frame 3 which itself is rockably carried on a supporting cradle 34 formed on the wheel slide so that the shaft 28 will not interfere with the proper angular adjustment of the casing 5 and of the wheel head. As shown in Figure 1, this wheel head or frame 3 may be provided with lugs 36 through which are passed the pivots 37 for the threaded adjusting rods 38 which are provided with knurled adjusting nuts 39 by which the angular position of the frame 3 and the central plane of the wheel may be adjustably fixed. The lower ends of the rods 38 may be pivotally secured as at 40 to any convenient part of the wheel slide. The rear end of the shaft 28 is provided with a suitable abutment 45 which determines the limit of inward motion of the truing mechanism toward the grinding wheel for any particular portion of the cycle of the truing mechanism. This abutment is arranged to be contacted by the inner end of an axially movable rod 50 carried by the angularly fixed member 6 and in alignment with the end of the shaft 28. In the inner end of rod 50 it is shown as supporting a ball 51 which directly engages the abutment 45, it being unnecessary that this rod 50 be rotated with the rotation of the shaft 28. The outer end of the rod 50 engages a ball at 52 supported in a socket at the lower end 53 of a lever 54 fulcrumed at 55 on the angularly fixed member 6. The upper end of this lever 54 is provided with a socket 56 for the reception of a ball 560 for engagement by the outer end of a thrust rod 57 slidably mounted in the casing 5 and coaxial therewith, so that for any angularly adjusted position of the casing 5 the rod 57 will be in proper alignment with the lever 54. It will be evident that, by moving the rod 57 forwardly within the casing from the position shown in Figure 4, the lever 54 will be rocked, and as it bears on the abutment rod 50 of the angular fixed portion 6, this rocking will permit the casing 5 to be moved forwardly to true the grinding wheel, while on moving the rod 57 backwardly to the position shown the casing 5 will be retracted from the wheel. This inward or truing motion may be effected by a pair of springs 60 one of which is shown in Figure 2. The outer end of each spring 60 is hooked over a pin 61 in a clip 62 secured as by a bolt 63 to the member 6, and its inner end is engaged with the end portion of a U-shaped link 64, the opposite end of which is pivoted at 65 to an arm 66 secured to a rock shaft 67. When the rock shaft is in the angular position shown in Figure 2, the corresponding spring 60 is under tension and presses the casing 5 as far as it is permitted by the angular position of the lever 54 toward the grinding wheel. By turning the shaft 67 counterclockwise as viewed in Figure 2, the tension on the spring 60 may be released, the arm 66 being then turned away from its dead center position with relation to the line of pull of the spring 60.

75 As shown in Figure 4, the inner end of the cas-

ing 5 is slidable through a packing ring 70 secured as by a retaining ring 71 to a flange 72 on the wheel head or frame 3, and back from the inner edge of the casing 5 it is shown as provided with a transverse partition 73 forming with the outside wall of the casing a chamber 74 within which are positioned the truing devices. As shown, there are three truing devices. Two of these devices 80 and 81 are supported on rock arms 82 and 83, respectively, which are secured to the end portions of a pair of rock shafts 84 and 85, so that these truing devices are eccentric to these rock shafts, whereby as these shafts are rocked the truing devices are caused to move transverse to the line of motion of the truing mechanism from and toward the wheel 1. The third truing device 86 which may be employed to true the extreme edge of the wheel, as, for example, in truing it to grind U. S. standard threads, is carried by an arm 87 fixed to a rockable and axially movable shaft 88. All of these truing device carrying shafts extend through the casing wall 73, preferably through suitable stuffing or packing glands, so as to prevent the entrance of grit from the wheel and other foreign matter back of the partition 73 and into contact with the actuating mechanism by which the motions of the truing devices are produced. The motions of these three shafts for effecting the lateral motions of the truing devices relative to the line of motion of the casing 5 are produced by power, as shown, this being derived from a motor 90 secured to the rear face of the casing 5 above the angularly fixed member 6. This motor, as shown in Figures 3 and 4, carries on its armature shaft a spiral gear 91 which meshes with a spiral gear 92 on a vertical shaft 93. This shaft 93 carries a worm 94 (see Figure 3) which meshes with a worm wheel 95 on a cam shaft 96 (see Figures 3 and 5) carrying a cam 97. The cam 97 is provided with a cam groove 98 therein in which rides a follower 99 on a rock arm 100 (see Figures 6 and 10). The rock arm 100 which is fulcrumed on the fixed pin 101 is provided with a pair of spaced gear segments 102 and 103. The gear segment 102 meshes with teeth on a rack sleeve 104 secured to the rod 57, so that, as the cam 97 is rotated, the rod 57 is moved axially alternately in opposite directions to retract the truing mechanism from the grinding wheel and then permit it to approach the wheel under the action of the springs 60. The segment 103 meshes with rack teeth on a slide 105 (see Figures 6, 7 and 10), this slide being guided for its motion on a pair of fixed guide bars 106 and 107 mounted in fixed relation on the inside of the casing 5. The slide 105 has adjustably secured thereto a former cam 108 having a cam edge 109. This former cam may be secured at one end to the slide 105 as by a bolt 110 and at its other end by a slot and bolt connection 111 which permits adjustment of the steepness of the slope of the cam edge 109. Cooperating with this former cam edge 109 is a cam follower block 115 supported at the end of an arm 116, rockably mounted at its opposite end on a hub 117 (Figure 4) of a rock arm 118 secured to the rock shaft 84. A screw abutment 1160 (Figures 6 and 7) may be carried by the arm 116 in position to ride, when desired, on the slide 105 when the follower 115 rides off from the former cam. The arm 118 and the arm 116 are adjustably related angularly through an adjusting screw 119 (Figures 2 and 6) threaded through the arm 118 and bearing against the arm 116. The arm 119 is held 75

with the adjusting screw 119 in contact with the arm 116 as by a spring-pressed plunger 1180. By adjustment of the angular position of the former cam 108 and the angular relationship between the arms 118 and 116, the rocking motion of the shaft 84 may be precisely controlled and correlated to the axial motion of the casing 5 so as to produce accurate control of the contour of the wheel side face trued by the truing device 80 which is carried by the rock arm 82 fixed to the shaft 84.

From the shaft 84 operative connections are provided to control the rocking motion of the rock shaft 85 which carries the truing device 81. As shown best in Figures 4, 5 and 8, these connections comprise an arm 120 carried by the shaft 84 and an arm 121 carried by the shaft 85. One of these arms, as the arm 121 shown in Figure 8, is slotted as at 122 for the adjustment toward and from the axis of the shaft 85 of a pivot 123 of a link 124, the opposite end of which is pivoted as at 125 to the arm 120. A spring 126 connecting these pivots at the ends of the link 124 take up any lost motion between the arms 120 and 121 so that the angular position of the shaft 85 is accurately but adjustably controlled by the angular position of the shaft 84. Thus the side truing devices 80 and 81 are accurately controlled, and, if desired, differently, so that the wheel may be trued with its side faces having the desired angular relationship to each other. The shape of the cam edge 109 of the former cam may also be varied as desired to play its part in the determination of the wheel contour trued by the side truing devices.

The third truing device 86 which trues off the extreme edge of the grinding wheel, as, for example, when it is desired to grind U. S. standard threads, is shown as actuated from the cam shaft 96. Referring particularly to Figures 5 and 9, the forward end of the cam shaft 96 is shown as provided with an edge cam 130, against which is pressed, as by a spring 132, a cam follower 131 carried by an arm 133 fixed as by a pin 134 transversely to the shaft 88. The opposite end of the arm 133 carries a cam follower 135 which rests against the end face of a cam member 136. This end face is inclined so that, as the arm 133 is rocked by the edge cam 130 about the axis of the shaft 88, it also gives the shaft 88 an axial motion, the follower 135 being held up against the cam 136 as by a coiled spring 137 surrounding the shaft 88 and reacting between the lever 133 and a bearing member 1340 in which the shaft 88 is journaled. The amount of this axial motion may be determined by adjusting the cam 136 angularly about its axis and the limits of this motion are determined by adjusting the cam 136 axially. The means for effecting these adjustments is shown best in Figure 11. The cam 136 is provided with a central shaft portion 137 flattened at its outer end as at 138 and engaging a slot 139 in a disk 140, so that, as the disk 140 is adjusted angularly, it turns the cam 136 therewith. The disk 140 is provided with an arcuate slot 141 therethrough within which rides a tightening screw 142 provided with a head 143 which may be clamped against the outer face of the disk 140. This clamps this disk against the outer face of a rectangular plate 145 which in turn bears against the outer face of a bearing 146 in which is threaded a sleeve 148. This sleeve 148 is provided with key projections 150 which engage correspondingly shaped slots extending from a central opening 151 of the plate through which

the portion 138 extends into the slot 139 of the disk 140. The plate 145 may be fixed in adjusted angular position by the adjusting screw 155 which passes through an arcuate slot 156 in the plate 145 and is threaded into the member 146. Thus, by adjusting the angularity of the plate 145, the sleeve 148 may be adjusted angularly and through its threaded connection with the frame member 146 axially, moving the cam 136 axially with it, while the cam 136 may be adjusted angularly by rotating the disk 140 to the desired extent. Adjustments having been made, the cam 136 is fixed in its adjusted position by tightening the bolts 142 and 155. Thus a very accurate adjustment of the motion of the truing device 86 may be had, its axial motion being superimposed on the axial motion derived by the motion of the casing 5, or, if the parts are so timed, the entire operative control of this third truing device is produced by the cam 130 and the cam 136.

The cam shaft 96 may also be employed to actuate certain controls for the various machine operations. For example, in Figure 5, a sleeve 200 may be fixed thereto, this sleeve having hub portions 201 and 202 of different sizes to which may be secured in any suitable manner the collars 203 and 204, respectively. These collars, as well as a flange 205 shown as integral with the sleeve 200, may be arranged as cams for controlling three electric switches 206, 207 and 208 shown in dotted lines in Figure 4. These switches and cam actuators may be so arranged that, after the motor 90 has been started by a suitable switch (not shown) at the end of a traverse between the wheel and the work, the first portion of the motion of the shaft 96 actuates one of these electric switches to slow down the speed of the grinding wheel 1, the normal cutting speed of which is too fast for the best effects in truing. Another of these switches may be actuated just prior to the completion of a single revolution of the cam shaft 96 to start the reverse traverse drive between the wheel and the work, and, as soon as this has been established and the cam shaft 96 completes one revolution, the third switch is actuated to stop the truing motor 90. These parts have not been shown in detail herein nor specifically described, since per se they form no part of the present invention.

In operation of the machine, the motor 90 is started at the desired time, as at the end of a traverse between the wheel and the work, and through its driving connections it rotates the cam shaft 96 and its cam 97 through a single revolution and is then automatically stopped by actuation of one of the cam collars 203 or 204, or the cam flange 205, the speed of rotation of the grinding wheel being slowed at or near the start of the cycle and returned to normal at or near the end of the cycle. This control action forms per se no part of the present invention, being set forth more in detail and claimed in the Flanders application Serial No. 94,903, filed August 8, 1936, for Grinding machine. Rotation of the cam 97 causes a complete oscillation of the rocker arm 100, which acts to impart a complete reciprocation of the thrust rod 57 causing the entire truing mechanism with its casing to move toward and then from the grinding wheel edge, imparting by this motion an in and out component of motion to all the truing devices. At the same time swinging of the arm 100 by the action of the cam 97 reciprocates the rack bar 105 which traverses the cam 109 relative to its fol-

lower 115. This rocks the arms 116 and 118 and the rock shaft 84 and through it the rock shaft 85 to impart lateral components of motion to the truing tools 80 and 81 properly co-related to the longitudinal motion component provided by the in and out motion of the entire mechanism, to true the side faces of the grinding wheel to the desired contours. At the same time the cam 130, with its motion modified by the cam 136, and also 10 by the in and out motion of the entire truing mechanism, produces the truing and return stroke of the end truing device 86. Periodic turning of the shaft 28 which adjusts the axial position of the rod 50 provides a further adjustment of the 15 reciprocal path of the truing mechanism to allow for reduction in diameter of the wheel through wear and truing.

In Figures 13 to 15 is shown means by which the operator may be aided in accurately setting 20 the speed of rotation of the grinding wheel in accordance with its decreasing diameter as it wears and is trued. The casing 5 of the truing mechanism is shown as provided with a scale 220 indicating in connection with a fixed part of the 25 machine, such as the edge of the mating stationary frame portion, the diameter in inches of the wheel for a definite position of the casing in its cycle with respect to the grinding operation. Since the truing devices are normally held just 30 out of contact with the grinding wheel for the major portion of the time of operation, this retracted position of the casing may well be that chosen for the correct indication. Thus, when the truing mechanism is retracted, the scale may 35 indicate the true diameter of the wheel and not the actual distance of the truing tools from the axis of the wheel.

In connection with this indicator, is a table 221 located in convenient sighting position for the 40 operator of the machine, and shown detached in Figure 13, this table showing for different wheel speeds and wheel diameters, the corresponding approximate surface speed in feet per minute. The wheel driving motor, indicated diagrammatically at 225, is a variable speed motor, as shown 45 being a direct current shunt motor with a field 226 variable by means of a rheostat at 227. By decreasing the field strength, as by interposing more of the resistance from the rheostat in the 50 field circuit in the well understood manner, the motor speed may be increased to compensate for decreasing wheel diameter due to wear and truing. The rheostat may have a hand control means, shown at 228 in Figure 12, with indications 55 thereon of the revolutions per minute of the grinding wheel. For any desired cutting surface speed in feet per minute, it is thus easy for the operator to adjust the rheostat control 228 in accordance with the table 221 for the desired 60 surface speed in accordance with the wheel diameter as indicated by the scale 220 when the truing mechanism is in any desired position of its cycle such, for example, as its retracted position. Of course, any other type of variable speed 65 motor might be employed with its properly marked speed control mechanism in place of the rheostat control of the field strength of a direct current motor.

From the foregoing description of an embodiment 70 of an invention shown by way of example and not of limitation, it should be evident to those skilled in the art that various changes and modifications may be made without departing from the spirit or scope of this invention as defined by the appended claims.

We claim:

1. In combination, a truing mechanism comprising a carriage, means supporting said carriage for motion toward and from a grinding wheel to be trued, said carriage including a truing device supporting portion angularly adjustable about an axis lying in the line of motion of said carriage, a truing device carried by said portion for motion laterally of said axis, means for moving said carriage toward and from the wheel, 5 means for moving said truing device relative to said carriage laterally of said axis, and connections from said carriage-moving means to said truing device moving means including a device correlating their relative motions to determine 10 the resultant path of motion of said truing device relative to the wheel having components of said carriage motion and the motion of said device relative to said carriage to thereby determine the 15 contour of the wheel face trued. 20

2. In combination, a truing mechanism comprising a carriage, means supporting said carriage for motion toward and from a grinding wheel to be trued, said carriage including a pair of parts one of which is angularly fixed and the other of 25 which is angularly adjustable relative to said fixed part about an axis lying in the line of motion of said carriage, a truing device carried by said angularly adjustable part, a lever fulcrumed on said fixed part, an abutment on which 30 another portion of said lever may engage, means yieldingly holding said lever in engagement with said abutment, and means for moving said lever to thereby move said carriage.

3. In combination, a truing mechanism comprising a carriage, means supporting said carriage for motion toward and from a grinding wheel to be trued, said carriage including a pair of parts one of which is angularly fixed and the other of 40 which is angularly adjustable relative to said fixed part about an axis lying in the line of motion of said carriage, a rod coaxial with the center of such angular adjustment, a truing device carried by said angularly adjustable part, a lever fulcrumed on said fixed part and having a portion 45 in alignment with said rod, an abutment on which another portion of said lever may engage, means yieldingly holding said lever in engagement with said rod and said abutment, means for moving said device, and means for moving said 50 rod axially to thereby move said carriage.

4. In combination, a truing mechanism comprising a carriage, means supporting said carriage for motion toward and from a grinding wheel to be trued, said carriage including a pair 55 of parts one of which is angularly fixed and the other of which is angularly adjustable relative to said fixed part about an axis lying in the line of motion of said carriage, a truing device carried by said angularly adjustable part for motion transverse to said line of motion, a lever fulcrumed on said fixed part, an abutment on which another portion of said lever may engage, means yieldingly holding said lever in engagement with said abutment, means for moving said 60 device, and means for moving said lever to thereby move said carriage.

5. In combination, a wheel-truing mechanism comprising a carriage, means supporting said carriage for motion toward and from a grinding 70 wheel to be trued, a rock shaft journaled in said carriage with its axis parallel to the line of motion thereof, an arm carried by said rock shaft, a truing device carried by said arm for truing a face of said wheel, means for rocking said shaft 75

to impart a component of motion to said device laterally of the line of motion of said carriage, means for producing said motion of said carriage, and means actuating said producing means and shaft-rocking means simultaneously correlated to produce a desired truing path of said device relative to said wheel face.

6. In combination, a wheel truing mechanism comprising a rock shaft, a truing device eccentrically connected to said rock shaft, an arm carried by said rock shaft, a cam follower carried by said arm, a reciprocable member, an edge cam carried by said member, means holding said follower against said cam, and means actuatable to reciprocate said member to thereby impart a wheel-truing motion to said device.

7. In combination, a truing mechanism comprising a carriage, means supporting said carriage for motion toward and from a grinding wheel to be trued, said carriage including a pair of parts one of which is angularly fixed and the other of which is angularly adjustable relative to said fixed part about an axis lying in the line of motion of said carriage, a truing device carried by said angularly adjustable part, a lever fulcrumed on said fixed part, an abutment on which another portion of said lever may engage, means yieldingly holding said lever in engagement with said abutment, means for moving said lever to thereby move said carriage, and means for adjusting the position of said abutment to compensate for wheel wear and truing.

8. In combination, a truing mechanism comprising a carriage, means supporting said carriage for motion toward and from a grinding wheel to be trued, a wheel truing device carried by said carriage, a lever fulcrumed on said car-

riage, an abutment carried by said supporting means on which another portion of said lever may engage, means yieldingly holding said lever in engagement with said abutment, and means for moving said lever to thereby move said carriage.

9. In combination, a truing mechanism comprising a carriage, means supporting said carriage for motion toward and from a grinding wheel to be trued, a wheel truing device carried by said carriage, a lever fulcrumed on said carriage, an abutment carried by said supporting means on which another portion of said lever may engage, means yieldingly holding said lever in engagement with said abutment, means for moving said lever to thereby move said carriage, and means for adjusting the position of said abutment with relation to said supporting means.

10. In combination, a wheel truing mechanism comprising a carriage, means supporting said carriage for rectilinear motion toward and from a grinding wheel to be trued, a pair of parallel rock shafts journaled in said carriage with their axes in the direction of said carriage motion, connections between said rock shafts for producing a simultaneous rocking thereof, a truing device eccentrically carried by each shaft for truing faces of said wheel, mechanism for rocking one of said shafts, means carried by said carriage and operatively engaging said supporting means for producing said motion of said carriage, and means actuatable to produce desired traversing paths of said devices relative to said wheel faces.
